[57] **CLAIM**

The ornamental design for a beverage dispenser, as shown and described.

DESCRIPTION

FIG. 1 is a perspective view of a beverage dispenser; FIG. 2 is a front elevational view; and FIG. 3 is a right side elevational view, with the left side elevational view being a mirror image thereof; FIG. 4 is a rear elevational view; and, FIG. 5 is a top plan view.

The push handles and buttons shown in dashed lines in FIGS. 1-3 are shown for illustrative purposes and form no part of the claimed invention.
